CHAIR CLAMP

George H. Towne, Waltham, Mass.

Application June 17, 1953, Serial No. 362,269

3 Claims. (Cl. 155—130)

1

The present invention relates to a device for holding adjacent chairs in fixed relation in a straight or curved row as in a public hall or the like.

When chairs, such as folding chairs, are set up in a row in a public hall it is desirable that they be held immovable in the row so as not to become disarranged as people move in and out of the seats.

Up to the present time, insofar as the inventor is aware, there has been no truly satisfactory device for this purpose. The devices which have been used are awkward to set in position, being either cumbersome to handle or having many bolts to tighten, and usually require tools to attach them to the chairs.

The present invention provides a device which is attached to the chairs simply and quickly and requires no tools to set it firmly in position, yet it will hold the chairs securely until released. It engages and holds two adjacent chairs at three points spaced apart in triangular relation and holds the chairs securely against movement relative to each other in any direction.

Further objects and advantages will be apparent from the following description of a preferred embodiment and the accompanying drawings in which:

Fig. 1 is a side elevation showing the device of the present invention attached to and in position on one chair.

Fig. 2 is a top plan view of the device attached to and in position between two chairs.

Fig. 3 is a prospective view showing the device in position holding two chairs together, parts of the chairs being broken away to reveal the device more clearly.

Fig. 4 is a view similar to Fig. 3, but showing a modified form of the present invention.

In the drawings the device of the present invention which holds two adjacent chairs in fixed relation is indicated generally at 10. The two chairs shown in connection with the device 10 are designated A and B and are one of a variety of folding type chairs such as are temporarily set up in public halls. The particular type and construction of the chairs A and B is shown for illustrative purposes only and it is to be understood that the device 10 is equally well adapted for use with rigid and folding chairs of varying construction so long as they include or may be adapted to include certain structural elements to support the device 10.

In the chairs A and B shown, the front legs 11 and back legs 12 cross and are pivoted at 13.

2

A seat 14 is pivoted between upward extensions of the back legs 12 and is supported at the back by links 15 pivoted on the seat and on the upward extension of the legs 11. Extensions of the lower ends of the links 15 are stopped against a stretcher 16 attached between the portions of the front legs 11 above the pivot points 13 and under the seat. The front legs 11 extend above the seat and form the frame of the back of the chair.

The device 10 of the present invention is comprised generally of a horizontal member 20 and a strut 21 having its lower end pivotally and slidably connected to a horizontal member. The device 10 is placed between two chairs A and B which are side by side. Both ends of the horizontal member 20 are forked to enclose respectively the two adjacent front legs and the two adjacent back legs of the chairs A and B and the forked ends are supported on stretchers 18 and 19 which are respectively across the front and back of the chairs. The ends of the forks hook over the stretchers to hold the horizontal member 20 in position.

As shown in Fig. 3, the horizontal member 20 is formed of a single rod bent double to provide two parallel rods 33 and 34 which are held in parallel relation by cross ties 35.

At the forward end a fork 23 passes inside the front leg 11 of the chair A and a fork 24 passes inside the front leg 11 of the chair B and the ends of the forks 24 are bent downwardly at 25 and 26 to hook over the front of the respective stretchers 18.

At the back end, the horizontal member 20 extends back between the adjacent rear legs 12 of the chairs A and B and a generally U-shaped member 27 attached across the back end forms the fork at that end. Forks 28 and 29, which are the arms of the U-shaped member 27 are directed back on the horizontal member and enclose the adjacent rear legs 12 of the chairs A and B between them. The ends of the forks 28 and 29 are bent downwardly at 31 and 32 to hook over the inside of the respective stretchers 19.

When the device 10 is put in position the horizontal member is dropped down on the stretchers 18 and 19. The downwardly bent portions 25, 26, 31 and 32 hooking over the front edges of the stretchers 18 and 19 prevent it from sliding backward. The U-shaped member 27 passing around the back of the legs 12 prevents it from sliding forward. Most chairs, both rigid and folding, have stretchers between the front legs

and between the back legs on which the horizontal member 20 may be supported as above. However, if there are no such stretchers, projections or studs secured on the insides of the legs will serve equally as well.

The strut 21 is pivotally and slidably connected to the horizontal member 20 by having its lower end 30 curled around a cylinder 36. The rods 33 and 34 of the horizontal member pass through holes parallel transversely through the cylinder so that the cylinder is slidable along the rods.

A U-shaped member 38 attached across the strut 21 down from its upper end 37 has arms 39 and 40 which form two parallel forked portions 41 and 42 with the respective edges of the strut 21. When the strut 21 is in position the adjacent upper portions of the legs 11 under the seats 14 of the chairs A and B are enclosed between the arms 39 and 40 of the U-shaped member 38 and the forked portion 41 encloses the stretcher 16 of the chair A and the forked portion 42 engages the stretcher 16 of the chair B.

It will be appreciated that the exact chair construction shown is not essential for the described engagement of the upper portion of the strut 21. A construction, including members which extend downwardly below the seat, such as the upper portions of the legs 11 under the seats, to be enclosed between the arms 39 and 40 and then extending inwardly, such as the stretchers 16, to be enclosed by the forked portions 41 and 42 would be similarly engaged.

For example, the device 10 is used with types of folding chairs which do not have a stretcher 16 but have an inwardly directed stud or rivet on the inside of the leg at approximately the same position which serves as a stop for a link such as the link 15 or to support the rearward end of the seat.

The strut 21 is made such a length that the forked portions 41 and 42 at its upper end 37 will enclose and firmly engage the stretchers 16 when its lower end 30 is in a position on the horizontal member 20 from which it may be moved in order to draw the forked portions 41 and 42 away from the stretchers 16 far enough to be swung clear of them. For example, the strut 21 is firmly engaged between the stretchers 16 and the horizontal member 20 when its lower end 30 is on the horizontal member which is closest to the stretchers 16. Thus, when the lower end 30 is slid along the horizontal member away from the mid-point, the upper end 37 will drop out of engagement with the stretchers 16.

As shown in Fig. 1, the stretcher 18 at the front of the usual type of folding chair is higher than the stretcher 19 across the back and when in position the horizontal member 20 will be slanted. Therefore, to disengage the upper end of the strut 21 from the stretchers 16 the lower end of the strut will be moved most easily toward the rear in the direction of the arrows C. Conversely, when the lower end of the strut is toward the rear of the horizontal member, the lower end 30 is moved forward in the direction of the arrow D to engage the upper end 37 with the stretchers 16.

In operation to attach this device 10 of the present invention to the two adjacent chairs A and B to hold them in fixed relation, the strut 21 is pivoted out of the way and the horizontal member 20 inserted between the chairs and dropped down into position enclosing the adjacent legs of the chairs and supported on the stretchers 18 and 19. The lower end 30 of the

strut 21 is slid toward the rearward end of the horizontal member 20. Then the strut is swung toward an upright position and guided into engagement with the stretchers 16 as its lower end 5 is slid in the direction of the arrow b. When the upper end 37 of the strut is in engagement with the stretchers, its lower end remains frictionally held in position on the horizontal member until the lower end is forcefully slid toward an end 10 of the horizontal member.

The device 10 as shown in Figs. 1, 2 and 3 is constructed to hold chairs side-by-side in a straight line. It will be appreciated, however, that it may be made to hold chairs in a semi-circular arrangement by changing the space 15 between the forks at the ends of the horizontal member 20 and between the forked portions at the upper end of the strut 21.

For example, Fig. 4 illustrates an embodiment 20 of the present invention which holds chairs in a semi-circle facing inward. The parallel rods forming the body of the horizontal member are bowed out at the rearward end as indicated at 25 43 to space the rear legs 12 apart and the central portion of the U-shaped member 27 is made correspondingly longer. The forks 23 and 24 at the forward end may be bent toward each other to fit around the front legs 11 snugly as indicated. The central portion of the U-shaped member 28 30 across the strut 21 is also lengthened to space the arms 39 and 40 further apart to enclose the upper portions of the legs 11.

It is to be understood that the above description is of a preferred embodiment of my invention 35 and that certain variations may be made in the structure without departing from the spirit of my invention.

What I claim as my invention is as follows:

1. A device for holding two adjacent chairs in 40 fixed relation, each of said chairs having two front legs, two back legs, a seat, inwardly extending projections on each of said legs, and a member extending downwardly and then inwardly below the seat at each side thereof, said device comprising in combination a horizontal member 45 each end of which has portions spaced apart sufficiently to receive between a leg of each of said two adjacent chairs, said portions being respectively supported on the inwardly extending 50 projections on the adjacent front and back legs of said chairs, a strut, and a slidably pivotal connection between the lower end of the strut and the horizontal member, the upper end of the strut being provided with two portions spaced apart to receive between them the members 55 which extend downwardly below the seats at the adjacent sides of the seats of said chairs and engage the respective inward extensions of said members, said strut being of sufficient length 60 to extend between said horizontal member and said downwardly and inwardly extending members when the lower end of the strut is in one position on the horizontal member but not when slid to another position.

2. A device for holding two adjacent chairs in fixed relation, each of said chairs having two front legs, two back legs, a seat, inwardly extending projections on each of said legs, and a member extending downwardly and then inwardly below the seat at each side thereof, said device comprising in combination a horizontal member having forked ends in which are respectively enclosed the adjacent front and back legs of said two adjacent chairs, the forks of the forked ends 70 being respectively supported on the inwardly ex-

tending projections on the respective legs of said chairs and having downwardly turned tips extending down past said projections, a strut, and a 5 slideable pivotal connection between the lower end of the strut and the horizontal member, the upper end of the strut being provided with two portions spaced apart to receive between them the members which extend downwardly below the 10 seats at the adjacent sides of the seats of said chairs, said two portions each being forked to engage the inwardly extending portions of the respective members, said strut being of sufficient length to extend between said horizontal member and said downwardly and inwardly extending members when the lower end of the strut is in one position on the horizontal member, but not when slid to another position.

3. A device for holding two adjacent chairs in fixed relation, each of said chairs having two front legs, two back legs, a seat, a stretcher between the pair of front legs and between the pair of back legs, and a stretcher under the seat across the chair from side to side, said device comprising in combination a horizontal member having forked ends in which are respectively enclosed the adjacent front and adjacent back legs

of two adjacent chairs, said forked ends being supported on the stretchers between the front legs and back legs of the respective chairs, a strut, and a slideable pivotal connection between the lower end of the strut and the horizontal member, the upper end of the strut being provided with two portions spaced apart to receive between them two adjacent legs of the two adjacent chairs, said two portions each being forked to enclose the respective stretchers under the seats of the two adjacent chairs, said strut being of sufficient length to extend between said horizontal member and said stretchers under the seats when the lower end of the strut is in one position on the horizontal member but not when slid to another position.
